UNITED STATES PATENT OFFICE.

SOLOMON K. MEYERHOFF, OF PHILADELPHIA, PENNSYLVANIA.

COLLAR.

SPECIFICATION forming part of Letters Patent No. 586,448, dated July 13, 1897.

Application filed March 24, 1897. Serial No. 629,054. (No model.)

To all whom it may concern:

Be it known that I, SOLOMON K. MEYERHOFF, a citizen of the United States, residing in Philadelphia, Pennsylvania, have invented 5 certain Improvements in a Combined Collar and Necktie, of which the following is a specification.

The object of my invention is to permanently combine a necktie with a collar, both 10 made of washable material, so that the necktie and collar can be laundered and can be used as an attachment to a shirt or in some instances may form part of a shirt or shirt-waist, as fully described hereinafter.

15 In the accompanying drawings, Figure 1 is a perspective view of my improved combined collar and necktie, showing the necktie tied in the form of a double bow. Fig. 2 is a sectional view. Fig. 3 is a perspective view of 20 the collar and necktie with the tie untied; and Figs. 4, 5, and 6 are views illustrating the different steps in making the tie.

A is a collar, in the present instance of a turned-down type. This collar has two short 25 extensions *a a*, provided with buttonholes, so that the collar can be secured to the shirt, and extending from the collar is the tie portion *B*, which is of a sufficient length to make a double-loop tie and a fastening. I preferably 30 form this portion *B* by splitting the neckband of the collar, one portion forming the short extension *a*, while the other forms the tie portion *B*; but it will be understood that the tie portion may be secured to the collar 35 permanently in any suitable manner. The end *b²* of the tie portion *B* is preferably reduced and stiffened.

b is a loop formed on the front of the portion *B* near where it joins the collar, and at 40 one side of the loop *b* in the portion *B* is a slot *b'* for the passage of the end *b²* of the tie when tied, so as to form a lock or fastening for the free end of the tie when worn, as this end *b²* passes back of the face-sec-

tion of the collar, as shown clearly in Figs. 1 45 and 2.

In using the combined collar and necktie the collar is first secured to the shirt in the ordinary manner and then the end *b²* of the tie portion is passed through the loop, as 50 shown in Fig. 5, forming a bow on one side, then turned in and passed back through the loop and through the slot *b'*, forming the loop on the opposite side, and the end of the tie portion when passed through the slot, as 55 shown in Fig. 6, extends back of the face-section of the collar, tending to hold the tie in proper position, so that the appearance is that of a detachable tie.

While I have shown the tie made of the 60 same material as the collar, it may be made of a different material without departing from my invention, and the style of collar may also be changed.

I claim as my invention—

1. As a new article of manufacture a combined necktie and collar having a collar portion, an extension on one end thereof, a loop on the extension and a slot so that the extension can be doubled upon itself and the 70 end passed through the slot to form a retainer for the tie, substantially as described.

2. A combined necktie and collar, of the collar-section having two short projections *a a*, buttonholes therein, with a long extension 75 *B* having a loop at a point near the collar, and a slot in the extension at one side of the loop, said extension having a reduced end so that by doubling the section through the loop and passing the end through the slot it will 80 form a tie, substantially as described.

In testimony whereof I have signed my name to this specification in the presence of two subscribing witnesses.

SOLOMON K. MEYERHOFF.
